UNITED STATES PATENT OFFICE.

ERNEST E. HEINTZ, OF DETROIT, MICHIGAN, ASSIGNOR TO TERMSTEDT MANUFACTURING COMPANY, OF DETROIT, MICHIGAN, A CORPORATION OF MICHIGAN.

WINDOW REGULATOR.

Application filed August 23, 1922. Serial No. 583,724.

To all whom it may concern:

Be it known that I, ERNEST E. HEINTZ, a citizen of the United States, residing at Detroit, in the county of Wayne and State of Michigan, have invented certain new and useful Improvements in Window Regulators, of which the following is a specification.

This invention relates to window regulators. It is the object of the present invention to provide a window regulator of relatively simple construction; this permits it to be economically built and opens a use for it on cheaper cars which have heretofore not been provided with window regulators. Furthermore, the regulator is so constructed and arranged that the handle may be installed at a variety of points across the door or window. This permits the proper placement of the regulator handle to meet with the requirements of the particular window or door. This and other features will more fully appear in the description following.

In the drawings,—

Fig. 1 is a side elevation of a door containing the regulator, the trimming being removed.

Fig. 2 is an enlarged elevation of the regulator.

Fig. 3 is a section on the line 3—3 of Fig. 2.

Fig. 4 is a section on the line 4—4 of Fig. 2.

Fig. 5 is a section on the line 5—5 of Fig. 2.

Fig. 6 is a section on the line 6—6 of Fig. 2.

Figs. 7, 8 and 9 are sections on the similarly numbered lines of Fig. 6.

Fig. 10 is a fragmentary section through the driving gears and elongated drum.

Fig. 11 is a detail in perspective of the drum and winding.

Fig. 12 is a perspective of the gear housing.

Fig. 13 is a section on the line 13—13 of Fig. 2.

The regulator is provided with the usual cross-strap frame *a* which carries at its bottom a pulley wheel *b* mounted on the carrier *c* which is provided with a pivot pin *d* (Fig. 4) by which it may both pivot and slide

through the ears *e* struck out of the strap frame *a*. The coil spring *f* forces the pulley wheel carrier downwardly and consequently serves to tension the cable *g*. This construction is described and claimed in the pending application No. 583,723.

The cable has its two ends fastened to the elongated drum *h*. One end winding around the drum in one direction and the other end winding around the drum in the opposite direction, as is plainly shown in Fig. 11. Consequently when the elongated drum is turned in one direction, one end of the cable unwinds and the opposite end winds up and vice versa, when the elongated drum is turned in the opposite direction. This construction eliminates an expensive chain and sprocket wheel. The elongated drum is nothing more than a common curtain roller provided with a tensional spring *i*, anchored at one end to the curtain roll and at the other end to the stationary shaft *j* (Fig. 6). By releasing the pawl *k* the ratchet wheel *m* may be turned to adjust the spring *i*. The spring *i* is a counter-balancing spring which is desirable in window regulators to make the window raise substantially as easy as it lowers.

One of the very important features of this regulator is the arrangement of the elongated drum with the keyway *n* in which the spiral gear *o* is loosely splined. Hence the spiral gear *o* may be freely slid along the elongated drum to any desirable position where the gear housing *p* is located.

In connection with rear quarter windows and the various door windows in an enclosed body, it is necessary very often to locate the regulator handle at different points, consequently with ordinary regulators it requires a different regulator construction for the several parts of the car. With the present construction, the housing *p* may be secured by screws to the lock board *q* at any point along the regulator plate *r*, which is secured to the lock board *s*. The key *t* is shown clearly in Fig. 3 and is secured to the worm.

The spiral gear *r* meshes with the spiral gear *o* and is rotatably supported in the housing *p* of the regulator.

This housing is secured to the inside of

the supporting plate *s* by the screws *t*. The regulator handle *u* serves to turn the worm gear *r*. A clutch 10 may be interposed between the handle and the regulator driving gear *r* if desired. Inasmuch as this clutch is not part of the invention, it is not here shown in detail. Whether a clutch is necessary will depend altogether on the pitch arrangement of the teeth of the spiral gears. If the pitch is small, the arrangement will be substantially irreversible and consequently no clutch is necessary. This arrangement may be adopted but the regulator handle will have to be turned a good many times to raise and lower the window; if a less number of turns of the handle is desired to raise and lower the window, then a clutch should be used.

What I claim is:

20 1. In a window regulator, the combination of a flexible draft member, upper and lower rotatable members over which the flexible draft member runs, and an actuating mechanism for the upper member which 25 may be permanently stationed in various positions with respect to the draft member laterally along the door or window for the purpose specified.

2. In a window regulator, the combination 30 of a flexible draft member, upper and lower rotatable members over which the flexible draft member runs, and a driving mechanism for the upper rotatable member adjustably fixable at various points along 35 said rotatable member for the purpose specified.

3. In a window regulator, the combination 40 of a flexible draft member, a lower rotatable member over which the flexible draft member runs, and a driving mechanism having a drive connection with the upper rotatable member which permits the driving mechanism to be slid along the upper member to fix said driving mechanism at various positions to accommodate the conditions met with in the body.

4. In a window regulator, the combination 45 of a flexible draft member, an upper and a lower rotatable member over which the flexible draft member runs, and a driving mechanism adjustably fixable at various points across the door or window by reason of having a slidably splined connection with the upper rotatable member.

5. In a window regulator, the combination 50 of a flexible draft member, a lower pulley wheel over which the same runs, an upper elongated drum around which the draft member winds, and a driving mechanism for the upper drum adjustable to various points along the drum for the purpose specified.

6. In a window regulator, the combination 55 of a flexible draft member, a lower pulley wheel over which the same runs, a trans-

versely extended elongated drum over which the draft member runs and a driving mechanism adjustable longitudinally of the drum for the purpose specified.

7. In a window regulator, the combination 60 of a pulley wheel, a flexible draft member winding over the pulley wheel, and an elongated drum over which the draft member winds at the top, a driven member splined on the elongated drum to slide along the same, and a driving member engaging the driven member and which may be placed at various points along the elongated drum, the driven member sliding along the drum to accord with such positioning.

8. In a window regulator, the combination 65 of a flexible draft member, a lower pulley wheel over which the draft member runs, an elongated transversely extending drum over which the draft member winds at 70 the top, a spiral gear splined on said drum to be slidable therealong, and a driving gear having a driving connection with the spiral gear and which may be placed at various points along the drum by reason of the 75 splined relation of the gear on the drum.

9. In a window regulator, the combination 80 of a lower rotatable member, a flexible draft member running thereover, an upper elongated drum over which the two upper 85 ends of the flexible member wind in opposite directions, a driven member slidable along the said drum and having a driving connection therewith, and means supportable at various positions along the drum for driving 90 the driven member.

10. In a window regulator, the combination 95 of a lower rotatable member, a flexible draft member running over said member, an upper elongated drum over which the flexible 100 draft member winds in opposite directions, a worm splined on said drum to slide therealong, and a driving mechanism which may be placed at various points along the drum to have a driving connection with the 105 said worm.

11. In a window regulator, the combination 110 of a flexible draft member, a lower pulley over which the same runs, a drum of the curtain roller type locatable directly under the window opening, means for positively 115 rotating said drum in either direction, a coiled spring contained in the said drum for equalizing the work of the rotating means in the upward and downward travel of the window sash, the said draft member having its ends winding in opposite directions over the drum and a device on an intermediate portion of the flexible draft member for connection with the window sash.

12. In a window regulator, the combination 120 of a flexible draft member, a lower pulley over which the same runs, a drum of the curtain roller type locatable directly under the window opening, a gear secured to the 125

drum to rotate the same, a driving gear for rotating the first mentioned gear in either direction, a coiled spring contained in said drum for equalizing the work of the gears in either direction, the said draft member having its ends winding in opposite directions over the drum and a device on an intermediate position of the flexible draft member for connection with the window sash. In testimony whereof I affix my signature. ¹⁰

ERNEST E. HEINTZ.
